CLAIM

The ornamental design for an insect repeller as shown and described.

DESCRIPTION

FIG. 1 is a perspective view of an insect repeller according to a first embodiment of the design;

FIG. 2 is a front elevational view thereof;

FIG. 3 is a back elevational view thereof;

FIG. 4 is a left side elevational view thereof;

FIG. 5 is a right side elevational thereof;

FIG. 6 is a top side elevational view thereof; and

FIG. 7 is a bottom side elevational view thereof.

FIG. 8 is a perspective view of an insect repeller according to a second embodiment of the design;

FIG. 9 is a front elevational view thereof;

FIG. 10 is a back elevational view thereof;

FIG. 11 is a left side elevational view thereof;

FIG. 12 is a right side elevational thereof;

FIG. 13 is a top side elevational view thereof; and

FIG. 14 is a bottom side elevational view thereof.

FIG. 15 is a perspective view of an insect repeller according to a third embodiment of the design;

FIG. 16 is a front elevational view thereof;

FIG. 17 is a back elevational view thereof;

FIG. 18 is a left side elevational view thereof;

FIG. 19 is a right side elevational thereof;

FIG. 20 is a top side elevational view thereof; and,

FIG. 21 is a bottom side elevational view thereof.

The broken lines depict portions of the insect repeller that form no part of the claimed design.
